ACCORDION GRILLE

Vincent Castiglione, Detroit, Mich.

Application December 6, 1956, Serial No. 44,091

Term of patent 3½ years

(Cl. D56—1)

Fig. 1 is a perspective view of an accordion grille showing my new design, an accordion body being shown in broken lines for purposes of illustration;

Fig. 2 is a fragmentary plan view thereof on a slightly larger scale; and

Fig. 3 is a sectional view along the lines 3—3 in Fig. 2.
I claim:

The ornamental design for an accordion grille, substantially as shown and described.
